JAMES A. KNOWLES, OF BALTIMORE, MARYLAND.

GRINDING-MACHINE.

1,367,150.

Specification of Letters Patent.

Patented Feb. 1, 1921.

Application filed February 27, 1920. Serial No. 361,853.

To all whom it may concern:

Be it known that I, JAMES A. KNOWLES, a citizen of the United States, residing at Baltimore city and State of Maryland, have invented certain new and useful Improvements in Grinding-Machines, of which the following is a specification.

This invention relates to machines for grinding the valves of motor-vehicle engines, and its object is to provide a simple and efficient machine of this kind which permits all the valves of an engine to be ground at one time, and which is entirely automatic in its operation.

The invention also has for its object to provide a novel and improved mechanism whereby the grinding operation is effected by an alternating rotary motion of the valves on their seats, the valves being periodically lifted off their seats to prevent the formation of scratches running around the entire circumference of the valves and the seats thereof.

Other objects and advantages of the invention will be pointed out in the detailed description appearing hereinafter, and in order that the same may be better understood, reference is had to the accompanying drawings forming a part of this specification.

In the drawings, Figure 1 is an elevation of the machine minus the cover of a gear case or housing; Fig. 2 is an enlarged section on the line 2—2 of Fig. 1 showing the valve assembly in place on the machine; Fig. 3 is a horizontal section on the line 3—3 of Fig. 1; Fig. 4 is an enlarged sectional detail on the line 4—4 of Fig. 3; Fig. 5 is a plan view showing the development of a cam; Fig. 6 is a diagram of a gearing; Fig. 7 is a sectional detail of a valve holder; Fig. 8 is a plan or end view of said holder, and Fig. 9 is a cross-section on the line 9—9 of Fig. 7.

The machine has been designed more particularly for grinding the valves of the Chevrolet motor, this type of motor having an upper removable cylinder block section 10 carrying the valve assembly. Fig. 2 shows this section, and one of the valves 11, with its stem 12. The design of the parts is such that when the section 10 is removed from the remainder of the cylinder block, the valve stems are left exposed and depending, as shown in Fig. 2. It will therefore be seen that by applying a rotatable

chuck or holder to the valve stem, the valve may be rotated back and forth on its seat and thus ground to obtain a perfect seating. The machine has been designed to grind the 60 entire set of valves simultaneously, and although the machine is adapted more particularly for Chevrolet motors, it is not limited thereto, but may be used for grinding valves of other motors in which the valve assembly 65 is such that the valve stems are accessible for attachment of a grinding tool.

The chuck or holder for the valve stem 12 consists of a rotatable and longitudinally slidable spindle 13 having at one end a head 70 14 on which seats a disk 15 forming the base of a shank 16 provided with a means for gripping the valve stem. The outer end of the shank 16 is enlarged and formed with a socket 17 to seat the end of the valve stem, 75 as shown in Fig. 7. On the outside of the socket end of the shank 16 are diametrically opposite ears 18 to which are pivoted, as shown at 19, levers 20 carrying latch pins 21 which extend through apertures in the 80 wall of the socket to enter the socket transversely and seat at their extremities in a transverse aperture in the valve stem. From the levers 20 extend pins 22 which are connected by springs 23 tensioned to normally 85 draw together the lever ends carrying the latch pins 21, thereby advancing the latter to holding position. Upon pressing the levers together to spread their ends carrying the latch pins, the latter are retracted to release the valve stem.

A loose connection is provided between the parts 14 and 15, to permit a limited degree of lateral play if the valve stem which is being held is slightly bent. By allowing 95 this lateral play, the valve is ground perfectly true and circular notwithstanding the bend in the valve stem, and the valve is not ground oval. The loose connection is obtained by bolts 24 passing through registering apertures 25 in the parts 14 and 15, said apertures being elongated radially. The parts 14 and 15 are also encircled by a coiled spring 26 tending to normally hold said parts in proper alignment, and yielding 105 to permit the lateral play hereinbefore referred to. The spring seats in a peripheral groove in the parts 14 and 15 at the contiguous faces thereof.

To the lower end of the spindle 13 is 110 fitted a pinion 27 for rotating the same. This pinion has a hub extension 28 seating

- in a bearing 29, and carrying at its upper end a collar 30 secured by a screw 31, and serving to prevent the pinion from slipping down in the bearing. The spindle 13 is free to slide up and down in the pinion and its hub, and in order to transmit the rotary motion of the pinion to the spindle, the pinion hub carries transverse screws 32 seating in a longitudinal groove 33 in the spindle.
- 10 The spindle 13 depends at its lower end from the pinion 27 so that said end may seat on a lifting cam 34. This cam is on a shaft 35 located in a housing 36 and supported at one end in a bearing 37 on one of the end walls of the housing. The other end of the cam shaft is supported by a partition 38 adjacent to the opposite end of the housing, and the cam shaft is also supported intermediate its ends by a bearing 39 rising from the floor of the housing.
- 15 Around the spindle 13 is fitted a coiled spring 40 for forcing the spindle downward to follow the cam 34. This spring seats at its lower end against an adjustable abutment 41 on the spindle, said abutment being a set-collar, and the upper end of the spring seats against an abutment 42 in the form of a washer seating against the under side of the top of the housing 36.
- 20 30 It will be evident from the foregoing, that the spindle 13 is rotated by the pinion 27, and that through the cam 34 and the spring 40 it is given a reciprocatory motion in the direction of its length. The valve 11 is held on its seat by the spring 40, and as the tension of this spring is adjustable by shifting the abutment 41, the degree of pressure of the valve against its seat can be readily regulated and varied to obtain the best results.
- 25 35 40 A valve operating means as hereinbefore described is provided for each valve, the shaft 35 having a number of cams 34, one for each spindle 13. The pinions 27 are also geared together as shown in Figs. 1 and 6. It will be noted in Fig. 6, that some of the pinions are not directly in mesh with each other, idlers 43 being provided. This is necessary as the spacing of the spindles, which conforms to the spacing of the valves, 50 is not uniform.
- 30 35 45 55 One end of the housing 36 is entered by a drive shaft 44 which latter, through a gearing to be presently described, imparts motion to a gear 45 which is in mesh with a gear 46 on the cam shaft 35, to drive the latter. The shaft 44 obtains motion from any suitable power source.
- 35 40 45 50 At one end of the train of pinions 27 and 43 is a pinion 47 for driving said train. This drive pinion is on a shaft 47 provided with a bevel gear 48 meshing with two oppositely facing bevel gears 49 and 50, respectively. The bevel gear 49 is keyed or otherwise made fast to a shaft 51, and the gear 50 is loose on said shaft. A spacing

sleeve 52 is interposed between the gears 49 and 50. The gear 49 has an extension provided with teeth to form a spur gear 53, and the gear 50 is in a like manner provided with a spur gear 54. The gear 45 is fastened on shaft 51 to turn therewith.

At 55 is shown a longitudinally slideable shaft carrying spur gears 56 and 57 fast on said shaft to turn therewith. The gear 56 is adapted to come in mesh with the gear 53, and the gear 57 in mesh with the gear 54, these pairs of gears being alternately intermeshed by sliding the shafts 55. The drive shaft 44 has a pinion 58 which is in mesh with a spur gear 59 on the shaft 55, whereby the motion of the shaft 44 is transmitted to the shaft 55.

The longitudinal sliding movement of the shaft 55 is obtained by a stationary abutment 60 seating in a cam groove 61 made in a collar 62 fast on said shaft. When the shaft 55 is rotating, the abutment 60 seating in the cam groove 61, causes the shaft to reciprocate, the cam groove being designed to give such a range of travel to the shaft 55 that the gears 56 and 57 are alternately carried into mesh with their companion gears 53 and 54. This change in the drive gears is for the purpose of changing the direction of rotation of the shaft 51, said shaft rotating in one direction when the gears 53 and 56 are in mesh, and the opposite direction when the gears 54 and 57 are meshing. It is also the object to vary the amount of turning movement of the shaft 51, said shaft being rotated alternately through different distances. Thus, the shaft 51 turns a certain distance when the gears 53 and 56 are in mesh, and a greater distance when the gears 54 and 57 are in mesh. This periodical and variable rotary movement of the shaft 51 is transmitted to the valves to be ground, through the gears 49, 50, 48, 47, 27 and 43. Fig. 3 shows the gears 54 and 57 in mesh, and hence motion is transmitted by the gear 50 to the gear 48, and as the gears 49 and 48 are also in mesh, and the gear 49 is fast on the shaft 51, said shaft also turns, and through the gears 45 and 46 the motion is transmitted to the cam shaft 35. When the shaft 55 is shifted to disengage the gears 57 and 54, and to bring the gears 56 and 53 into mesh, the shaft 51 receives motion as before, but in the opposite direction, through the gear members 49 and 53 as they are fast on the shaft, and hence the cam shaft 35 is also again driven. The gear 48 is now rotated by the gear 49, the gear members 50 and 54 turning idly on the shaft 51. The motion transmitted to the gear 48 by the gear 49 is transmitted to the valve-engaging spindles 13 as before.

It will be evident from the foregoing that the valve grinding operation is effected by rotating the valves on their seats, they be-

ing rotated alternately in opposite directions. The valves are given a greater number of turns in one direction than in the other. This result is attained by letting the 5 gears 57 and 54 remain in mesh longer than the gears 56 and 53, and the gears are thus timed by the particular design of the cam groove 61. Referring to Fig. 5, it will be seen that the cam groove has one portion *a* 10 which is longer than the other portion *b*, and hence the shaft 55 will remain in the position to which it is shifted by the portion *a* for a greater length of time than in the position to which it is shifted by the portion *b*. The operation of the spindle lifting 15 cams 34 is so timed that the lift occurs during the intervals when the direction of rotation of the shaft 51 is changed. By rotating the valves on their seats in one direction, then lifting the same and repositioning them on their seats, and continuing the rotary movement in the opposite direction, a good seating is assured, and as the extent 20 of the rotary movement in the respective directions is not the same, the rotary movement always starts in a different position of the valves, so that the formation of continuous ridges or scratches is prevented.

The abutment 60 is on a post 63 rising 25 from the floor of the housing 36, and said housing is also provided with suitable supports for the various shafts hereinbefore described. The shaft 44 enters the housing through a stuffing box 64. The housing 35 will be made fluid-tight so that it may hold a lubricant in which the gears run.

From the top of the housing 36 rise standards 65 supporting the cylinder block section 10 as shown in Fig. 2. These standards 40 will be grouped to enter certain bolt holes in the part 10, and they are shouldered to prevent said part from slipping down. The spindles 13 are grouped to correspond to the grouping of the valves, so that they may 45 be coupled to the valve stems when the part 10 is placed on the standards 65.

I claim:

1. In a valve grinding machine, a spindle, 50 a head on said spindle, a valve-stem gripping means having a base seating on the aforesaid head, a loose connection between the head and the base, and a yielding member encircling the base and the head for normally holding said parts in alinement.

55 2. In a machine for grinding the valves of internal-combustion engines, a housing, standards rising from the housing for supporting a valve-carrying member above the housing, a plurality of valve-grinding spindles in the housing, said spindles projecting from the top of the housing and having their upper projecting ends provided with means for gripping the stems of valves 60 projecting from the valve-carrying member,

and means in the housing for operating the 65 spindles.

3. In a valve grinding machine, a rotatable and longitudinally slidable valve-grinding spindle having valve-gripping means, a bevel gear, driving connection between the bevel gear and the spindle, a pair of oppositely facing bevel gears in mesh with the aforesaid bevel gear, a shaft supporting the pair of bevel gears, one of said gears being loose on the shaft and the other 70 one being fast on the shaft, spur gears for rotating said pair of bevel gears, drive gears alternately engageable with the spur gears, a drive shaft carrying the drive gears and longitudinally slidable to engage 75 the spur gears, means for effecting such sliding movement of the last-mentioned shaft, a cam for sliding the spindle in a direction to lift the valve off its seat, a shaft carrying the cam, and a driving connection 80 between the first-mentioned shaft and the cam shaft.

4. In a valve grinding machine, a rotatable and longitudinally slidable valve-grinding spindle having valve-gripping 90 means, a bevel gear, driving connection between the bevel gear and the spindle, a pair of oppositely facing bevel gears in mesh with the aforesaid bevel gear, a shaft supporting the pair of bevel gears, one of said 95 gears being loose on the shaft and the other one being fast on the shaft, spur gears for rotating said pair of bevel gears, drive gears alternately engageable with the spur gears, and for different lengths of time, a drive 100 shaft carrying the drive gears and longitudinally slidable to engage the spur gears, means for effecting such sliding movement of the last-mentioned shaft, a cam for sliding the spindle in a direction to lift the 105 valve off its seat, a shaft carrying the cam, and a driving connection between the first-mentioned shaft and the cam shaft.

5. In a valve grinding machine, a rotatable and longitudinally slidable valve-grinding spindle having valve-gripping means, a bevel gear, driving connection between the bevel gear and the spindle, a pair of oppositely facing bevel gears in mesh with the aforesaid bevel gear, a shaft 110 supporting the pair of bevel gears, one of said gears being loose on the shaft and the other one being fast on the shaft, spur gears for rotating said pair of bevel gears, drive 115 gears alternately engageable with the spur gears, a drive shaft carrying the drive gears and longitudinally slidable to engage the spur gears, a collar on the last-mentioned shaft, said collar having a cam groove, a stationary abutment seating in the cam 120 groove for effecting the sliding movement of the shaft, a cam for sliding the spindle in a direction to lift the valve off its seat,

a shaft carrying the cam, and a driving connection between the first-mentioned shaft and the cam shaft.

6. In a valve grinding machine, a rotatable and longitudinally slideable valve-grinding spindle having valve-gripping means, a bevel gear, driving connection between the bevel gear and the spindle, a pair of oppositely facing bevel gears in mesh 10 with the aforesaid bevel gear, a shaft supporting the pair of bevel gears, one of said gears being loose on the shaft and the other one being fast on the shaft, spur gears for rotating said pair of bevel gears, drive 15 gears alternately engageable with the spur gears, a drive shaft carrying the drive

gears and longitudinally slideable to engage the spur gears, a collar on the last-mentioned shaft, said collar having a cam groove, a stationary abutment seating in the 20 cam groove for effecting the sliding movement of the shaft, said cam groove being shaped to hold the drive shaft slid in one direction for a greater length of time than in the other direction, a cam for sliding the 25 spindle in a direction to lift the valve off its seat, a shaft carrying the cam, and a driving connection between the first-mentioned shaft and the cam shaft.

In testimony whereof I affix my signature. 30

JAMES A. KNOWLES.
